UNITED STATES PATENT OFFICE.

FRANK C. DE REAMER, OF SCHENECTADY, NEW YORK, ASSIGNOR TO
GENERAL ELECTRIC COMPANY, A CORPORATION OF NEW YORK.

ROTARY SWITCH.

No. 841,234.

Specification of Letters Patent.

Patented Jan. 15, 1907.

Application filed July 21, 1904. Serial No. 217,456.

To all whom it may concern:

Be it known that I, FRANK C. DE REAMER, a citizen of the United States, residing at Schenectady, county of Schenectady, State of New York, have invented certain new and useful Improvements in Rotary Switches, of which the following is a specification.

The present invention relates to rotary electric switch cut-outs, and more particularly to that class of such devices in which the conductor parts are inclosed or concealed from view. The inclosed switches in common use are made up of an insulating-base part upon which the stationary and movable contacts are mounted, a cap or plate engaging one side of the base and serving as a finished housing for the operative parts, and a thumb-nut which extends through the cap or plate and is connected to the movable switch member to actuate it and also in some instances to hold the cap or plate close up to the base part.

It has been customary heretofore in order to indicate whether the movable contact of an inclosed switch cut-out were in open or closed position to provide an index plate or finger upon the spindle of the movable member; but this is objectionable on account of interfering with the esthetic appearance of the switch.

The object of my invention is to provide adjustable means whereby the thumb-piece of a switch cut-out may be so positioned relatively to the movable contact that the thumb-piece will visually indicate the position of the movable contact relatively to the stationary contact.

A further object of my invention is to provide an improved stationary contact which is more durable and less expensive to manufacture than the contact heretofore in use.

For a complete understanding of my invention reference may be had to the following description and the accompanying drawings, forming a part of this specification, in which—

Figure 1 is a vertical transverse section of a flush wall-switch with my invention applied thereto. Fig. 2 is a vertical longitudinal section thereof with the thumb-nut and part of the actuating-shaft removed. Fig. 3 is a top plan of the switch with the thumb-nut and face-plate removed. Fig. 4 is a side elevation of a stationary contact.

The base 1, which is of molded porcelain, is made cup-shaped, with a peripheral wall 2, having recesses 3 formed in its inner surface for the reception of the binding-posts 4. To the inner surface of the bottom of the base 1 a snap-switch 5 of any suitable construction is secured. As shown, the switch consists of a stop-plate 6, secured rigidly to the base by projections extending through apertures and soldered at 7; an actuating-spindle 8, free to turn in the stop-plate 6, but held from longitudinal movement by a shoulder 9, beneath the plate; a catch-plate 10, having a central hub 11, through which the spindle 8 passes, and two opposite wings 12, having means at their lower edges for engaging the stop-plate; a helical spring 13, surrounding the spindle and engaging at its ends with the spindle and the catch-plate 10; a switch-blade 14, consisting of a metal punching with a central aperture through which the catch-plate 10 is free to slide, and a pin 15, carried by the spindle 8 and engaging the upper surface of the blade 14 to hold it from rising, and the lower edge of the catch-plate 10, which is formed in the shape of a cam 16, so that when the spindle is rotated clockwise the spring 13 is first put under tension and as the pin 15 reaches the lowermost part of the cam 16 the catch-plate 10 is freed from the stop-plate 6 and rotates under the recoil of the spring through a quarter of a circle, carrying the switch-blade with it. In the larger sizes of switches a second switch-blade is mounted some distance above the first, so as to break the circuit in both sides.

The stationary contacts 17 consist of U-shaped phosphor-bronze springs each having an end of one arm bent over to form a shoulder 18 and riveted to an arm of the binding-post 4. By securing the contact 17 to the binding-post, as shown in Fig. 2, the bearing-surface is in position to engage the contact-blade 14; but by inverting the contact 17 its bearing-surface is brought into proper position for engaging the upper blade of a two-blade switch, and as a consequence of this arrangement but a single set of punchings is necessary.

The upper end of the base 1 is closed by a flat face-plate 19, having a central aperture 20 for the passage of the spindle 8 and is held from displacement in its plane by pins or screws 21, which engage sheet-metal ears 22,

extending outwardly from the upper surface of the base and having countersunk holes 23 for the screws, by which the switch is secured in place.

5 The thumb-piece 24 is connected to the outer end of the spindle 8 by screw-threads in the usual manner and has a shoulder 25 turned thereon for engagement with the outer surface of the face-plate. By screwing the 10 thumb-piece down upon the face-plate the latter is clamped upon the wall of the base, and by adjusting the thumb-piece rotarily into parallelism or at right angles to the switch-blade 14 it will indicate the position 15 of the latter relatively to its stationary contacts. The means for securing the thumb-piece 24 in adjusted position without interfering with its ready removal consists of a flanged collar 26, threaded upon the spindle 8 and provided with a clamping-screw 27, by which it is held from being rotated out of its adjusted position.

I do not desire to restrict myself to the 25 particular form or arrangement of parts herein shown and described, since it is apparent that they may be changed and modified without departing from my invention.

What I claim as new, and desire to secure by Letters Patent of the United States, is—

30 1. The combination with a rotary-switch mechanism and its cover-plate, of a thumb-piece screw-threaded to the shaft of said

switch, and a shouldered collar screw-threaded to said shaft and adapted to abut against the end of said thumb-piece. 35

2. The combination with a rotary-switch mechanism, and its cover-plate, of a thumb-piece screw-threaded to the shaft of said switch, a shouldered collar screw-threaded to said shaft for holding said thumb-piece in adjusted position, and means for clamping said collar to the shaft. 40

3. The combination of a binding-post provided with a projecting arm, and a U-shaped spring-contact having one arm bent over at 45 its end to form a shoulder and secured to said projecting arm of the binding-post with the shoulder in engagement with an edge thereof.

4. The combination with a spring-contact, 50 of a sheet-metal post having its opposite ends bent up at right angles thereto to form a foot and a binding-plate and a side arm turned up from one edge of the foot and bent outwardly at right angles to the edge of the post, and 55 means for securing said contact to said side arm.

In witness whereof I have hereunto set my hand this 19th day of July, 1904.

FRANK C. DE REAMER.
